UNITED STATES PATENT OFFICE.

ALFRED L. CAMPBELL, OF ELMHURST, NEW YORK, ASSIGNOR TO BREWSTER & CO., A CORPORATION OF NEW YORK.

DESIGN FOR A THROTTLE AND SPARK CONTROL BRACKET FOR MOTOR-CARS.

49,919.

Specification for Design.

Patented Nov. 21, 1916.

Application filed August 22, 1916. Serial No. 116,395. Term of patent 14 years.

To all whom it may concern:

Be it known that I, ALFRED L. CAMPBELL, a citizen of the United States, residing at Elmhurst, Long Island, in the county of Queens and State of New York, have invented a new, original, and ornamental Design for a Throttle and Spark Control Bracket for Motor-Cars, of which the following is a specification, reference being had to the accompanying drawing, forming part thereof.

Figure 1 is a plan view of a throttle and

spark control bracket for motor cars showing my design. Figs. 2 and 3 are different side views of the same.

I claim:

The ornamental design for a throttle and spark control bracket for motor cars, substantially as shown.

ALFRED L. CAMPBELL.
